PATCH APPLYING MACHINE

Abraham Novick, Flushing, N. Y., assignor to
 F. L. Smithe Machine Co., Inc., New York,
 N. Y., a corporation of New York

Application July 1, 1937, Serial No. 151,463

12 Claims. (Cl. 93—61)

This invention relates to a machine for applying to the walls of envelopes attachments of various sorts, such as clasp fasteners of the type illustrated in Letters Patent No. 1,827,901, issued to me on October 20, 1931, these fasteners being each formed out of a single piece of sheet metal of approximately cruciform shape, comprising elongated tongues extending in opposite directions from a central web, with attaching lobes 10 extending in opposite directions from the same web, preferably at right angles to the major axis defined by the tongues, and having an attachment portion or portions riveted through the ply or plies of wall material at the region over which the cover-flap is to be folded.

Machines are known for attaching such fasteners to the back walls of envelopes, so disposed that when the tongues are bent up out of the plane of the envelope toward each other, they 20 may be passed through a hole in the cover-flap and then bent back over the margins at opposite sides of the hole, to retain the cover-flap in closed position.

The present invention constitutes an improvement upon this type of machine, and may be embodied in various machines of the type, as for example, such a machine as that disclosed and claimed in my co-pending application, Serial No. 142,393, parts of which are hereinafter illustrated in somewhat schematic form to aid in the understanding of the present invention.

In the machine of the present invention, means are provided, preferably as disclosed in said co-pending application Serial No. 142,393, for clinching the clasp fastener to the envelope body, and for applying a patch to the cover-flap, and perforating the flap thus reinforced.

An object of the present invention is to provide mechanism, at a station spaced from the clinching station, for applying a patch of adhesive material to the inside wall of the envelope and so disposed that the patch will cover the already clinched attachment portion of the clasp fastener exposed within the envelopes, such 45 mechanism being designed to squash the said exposed attachment portion still further and cause the same to be embedded in the contiguous surfaces of the sheet material out of which the patch and wall plies are formed, thus decreasing the 50 total thickness of the envelope walls at the region of the cover-flap fastener, both when the cover-flap is fastened in its closed position, and when it is simply folded over.

Such decrease in thickness of a combined 55 envelope wall and clasp fastener with a protective

patch has the advantage over an envelope provided with a fastener which is simply squashed, but not provided with a protective patch and therefore not embedded between adjacent layers of material, that when the envelopes are stacked, there is less tendency for the fasteners to mark the contiguous surfaces of adjacent envelopes in the stack; and also the stack can be made more compact and even.

A cognate object of the present invention is to 10 provide such a patch which will serve to protect the goods inside the envelope from damage or wear or marking by the fastener; and this is particularly important in the case of goods made of flimsy material, such as stockings, which, if 15 they are permitted to hook on to the fastener prongs, will develop runs during the operation of inserting them, or when subjected to abrasion by the rough upset fastener parts when the envelope is carried by a purchaser, or is in transit through 20 the mails.

The patch helps also to reinforce the envelope walls, by reason of the sticking of the patch to the envelope material, and it resists the tearing strain on the material, thus aiding to hold the 25 material together.

Another object of the invention is to provide a machine of the above type with mechanism, including an anvil, to which the adhesive patch sheet is first transferred, and is attached temporarily thereto; and by which anvil the patch is carried, with its wet, gummy side presented upwardly, into the open end of the envelope, and is there disposed in suitable position for completion of the operation of squashing and protecting the 35 fastener.

Other objects and advantages of the invention forming the subject of the present application will appear as the description of the particular physical embodiment of the invention selected for 40 illustration and description progresses.

In the accompanying drawings, like characters of reference have been applied to corresponding parts throughout the several views which make up the drawings, in which:

Fig. 1 is a view of a schematic character in vertical sectional elevation, of a fastener-applying machine in the construction of which the present invention has been embodied;

Fig. 2 is a plan view of a completed envelope with a fastener and protective patches applied thereto by the mechanism illustrated in Figs. 1 and 3;

Fig. 3 is a view in plan, of a schematic char-

acter, showing part of the machine illustrated in Fig. 1;

Fig. 4 is a similar view of a schematic character, showing in plan certain of the other operating parts illustrated in Fig. 1; this figure being complementary to the showing of Fig. 3;

Fig. 5 is a fragmentary, detail view in horizontal section, taken on the line 5—5, of Fig. 7, illustrating the cooperating parts associated with the operation of severing from a stock strip a patch blank and delivering it to the anvil plate by which it is to be transferred to a patch-applying station and there affixed in protective relation over the area of the inner envelope wall occupied by a squashed fastener;

Fig. 6 is a fragmentary detail view in plan of the anvil, showing the means by which a suitable protective patch is supported on the anvil for introduction to the open end of an envelope;

Fig. 7 is a fragmentary, detail view in vertical, longitudinal section illustrating typical mechanism for applying a reinforcement patch, this view being taken on the line 7—7 of Fig. 5;

Fig. 8 is a vertical, sectional view, similar to Fig. 7, taken on the line 8—8 of Fig. 5;

Fig. 9 is a fragmentary, detail view in plan on an enlarged scale, of the fastener element and associated fastener means, after completion of the operation by which the fastener and its patch have been applied;

Fig. 10 is a view in transverse section on the line 10—10 of Fig. 9.

In a now-preferred embodiment of the invention selected for illustration and description, referring first to Figs. 1, 3 and 4, the parts designated by the reference characters B' and B'' are endless belts constituting a conveyor around which the means for performing the operations which characterize the present invention are organized. This belt conveyor runs upon pulleys 41 and 42, the latter of which is mounted on a countershaft 43, driven by the main driving shaft 1 through bevel gears 44 and 45.

At S is shown a means for supplying to the conveyor a series of envelopes E, derived successively from a stack S thereof, supported suitably by the adjustable plates 11, and from the bottom of which each envelope which at any time constitutes the lowermost component of the stack is transferred to the conveyor belts B', B'', by the transfer mechanism illustrated in Figs. 1 and 3.

In the instance illustrated, the transfer mechanism comprises a rotor device made up of two rotary elements R' and R'', spaced apart on the shaft 30, and each provided with a set of gripper members G, each of which is mounted pivotally upon the periphery of one of the rotor elements, upon which it can be oscillated, as by a cam 26, to grip the free or leading end 12 of the then lowermost blank, when the latter has been separated from the stack, as indicated in Fig. 1. For further details of the mechanism, reference may be had to my aforesaid co-pending application Serial No. 142,393.

The separation above mentioned is effected by a sucker S' carried by a bail 20 which is swung about an axis 21, being mounted on a suitable support 18, (see Fig. 1) and through which the suctional effect is exerted from a source not shown, in suitably timed relation with the rotative movement of the rotors B' and B'', to pull along the free end 12 of an envelope immediately after arrival of the grippers G at the point shown in Fig. 1.

This operation does not require further de-

scription, and it will be readily understood by those skilled in the art that as the grippers G draw each envelope E around the periphery of the rotor elements B', B'' the leading end 12 of the envelope will soon be entrained between the rotor elements R', R'' and the conveyor belts B', B'', whereupon the suction will be cut off in known fashion by suitable means (not shown).

Movement of the belts B' and B'' in the direction of the arrow (Fig. 1) carries with them the envelope just received from the rotors, and advances it to a station at which it is arrested, as by a pair of fingers or stops 53, the fingers being moved upward into the path of the advancing envelope E by suitable means, illustrated as a block 55, mounted on a link L, which in turn is carried by a pair of crank arms 29, 29 rotatable about pivots 29x, and connected by another link L', so that parallel vertical movement of the stop fingers 53 is assured.

When in the elevated position illustrated in Fig. 4, the stops 53 are engaged, at spaced points, with the leading edge (bottom) 12 of an envelope which is thereby positioned suitably for the performance thereon of a patch-applying operation and a patch perforating operation at a suitable station, as at A'', (see Fig. 1), and concurrently for the performance of a fastener-applying operation, as at the station designated generally by the reference character A'. No description of these operations in detail need be made herein, inasmuch as they are merely illustrative of a variety of such attachment or other operations, and a full description of the preferred form of mechanism by which they may be effected is to be found in my co-pending application Serial No. 142,393, to which reference has already been made.

It will therefore be sufficient to say that the envelope is first fed beneath the anvil V up to the point of its arrest by the fingers 53, which have been raised into the path of the envelope by the action of a lever tension spring 59, operating on a crank 59x, which tends to bias the crank counter-clockwise, lifting the link L on which is mounted the block 55 that carries the fingers 53. A crank 61 on the shaft 60 is connected by a link Lz with a cam lever 62 mounted pivotally on an arm 63 which has a follower 64 engaged with a cam 65 upon the counter-shaft 1x, and this cam acts to retract the fingers 53 positively to their lower position shown in full lines in Fig. 1.

Fasteners are supplied to the fastener-applying station A' through a chute C, as described in my co-pending application, Serial No. 142,393, and are clinched in the usual, or any suitable manner. Patch strip S'' is advanced in the manner described in said application and is moistened at 131x, being fed by rolls 131 and 132 through a trough 165 to the station A'', where the strip is severed suitably, it is pressed down upon the flap, and perforated, all as described in said application, or in any suitable manner after the anvil V has been advanced from the position shown in full lines in Fig. 3, to a position in which it is aligned with the plunger P3, and in which it clears the patch-applying plunger 128, and enters the open end 13 of the envelope.

Suitable means are provided, as at 82, Fig. 3, to cause adequate opening of the walls of the envelope, the finger 82 being raised momentarily to buckle the walls and then being retracted positively by the action of a lever 86 rocked for that purpose by the cam C'' upon the driving shaft 1.

The advance and retraction of the anvil V

are accomplished through the arm V' by a carriage 200 (see Fig. 3), sliding in ways 201 and pushed forward by a link 102 spring-biased to its forward position, by a spring 104x, the retraction of the anvil being performed positively by the action of a cam C3 upon the countershaft 1x, engaged with a follower 107 carried by a pitman 104 connected to the pitman 104.

This mechanism is all fully described in my 10 aforesaid co-pending application.

The drawings of the present application illustrate, in somewhat schematic form, only enough of the operating parts to show how the various steps involved in the attachment of each clasp 15 fastener to its envelope are performed successively in pursuance of the present invention, this attaching operation comprising several steps, of which the preliminary step, which for the sake of brevity, is herein termed the clinching step, has 20 been performed at the station A' as already described.

A final, or squashing step, is performed at the station A3, the reference character T' serving to designate the setting or squashing tool, 25 which is used to perform the squashing operation.

Each envelope, and the pair of carrier belts, as B' and B'', by which the envelopes are advanced, is supported against the action of the 30 various tools, such as plunger P2, plunger 128, plunger P3, plunger T'', etc., by suitable devices, which will be termed anvils respectively, including stationary anvils A and Ax, at the clinching and squashing stations respectively and moveable 35 anvil plates V and V4 which are connected by their respective shanks V' to a link Vx which moves the anvil plates V and V4 simultaneously from the full line position shown in Fig. 4, to an advanced position in which each anvil rests below 40 one of the plungers.

It is to be noted particularly that the envelopes are fed in the direction of the major axis, and that the shape and feed of the anvil plates is so designed that the anvil plates are introduced into 45 the open ends of the envelopes by a movement parallel with the direction of travel thereof.

When in an advanced position, ahead of the 50 position of Fig. 1, and Fig. 3, the anvil head-plate V, stands clear of the thrust of the punching tool P2 as it forms the hole 9 in the envelope closing flap 10 (see Fig. 2), and in the reinforcement patch P' which is set in adhered position on the flap as hereinbefore described. The thrust of the punch is met by a suitably disposed part of 55 the main anvil VB.

The bar V' (see Fig. 3) is moved in a right-hand direction from its full-line position to cause the anvil head-plate V to enter the open end of the envelope, its entrance being facilitated by the 60 action of a finger 82, which when raised, as by the suitable means, not shown, causes separation of the overlapping rear walls e and e' of the envelope, so that ample clearance is provided for entrance of the anvil V at the region where the 65 overlapped plies are ready to be transfixed by the fasteners.

After the fastener has been transferred from the chute C by descent of the tool P3 the stops 53 are depressed by the movement in right hand 70 direction of the link LZ, and the envelope E is released for further advancement by the belts B' and B'' which carry the envelope forward until its bottom edge 12 is arrested by a pair of stops 54 (see Fig. 1), which are identical in all 75 essential respects with the stops 53, being so

spaced from the latter that when the envelope is so arrested by the stops 54, the fastener F' which has been clinched in place by the punch P3 against the anvils V2, is disposed in correct alignment with the squashing tool T' over 5 the stationary anvil V3.

While the envelope has been thus brought to the squashing station, another envelope has been fed to the clinching station A', and at the same time that the link 102 is moved in right-hand 10 direction to insert the anvil headplate V in the envelope at the clinching station, it acts, through a link 102x, Figs. 3 and 4, to insert the anvil head-plate V4 into the rear end of the envelope occupying the squashing station, this end of the 15 last-named envelope being opened up for insertion of the anvil V4 by a finger 82x, Fig. 4, which operates upon the envelope walls in repetition of the opening step already described with reference to the similar parts hereinbefore disclosed. 20

In pursuance of a further object of the present invention, means are provided to apply to the inner wall 46 of the envelope, (see Figs. 2, 9 and 10) a patch PX which will completely cover the inner end 6x of the clasp fastener element, whatever be its character, and will entirely prevent contact therewith by the contents of the envelope, so that the user is assured of optimum safety from injury to the most delicate fabrics and surfaces by any part of the fastener structure. 30

To accomplish this purpose, the present invention provides for severing a patch sheet PX from a supply strip Wx of gummed fabric, such as a tough Kraft paper, cloth or the like, which is fed across the path of travel of the envelope in suitably timed movement to bring the leading end PX of the patch strip over the anvil V4 (see Fig. 7) when it is in its position of Figs. 1, 3 and 7. En route from the supply roll W3, the previously 40 gummed upper face of the strip Wx is remoistened by a roll 222 which derives moistening fluid from a supply thereof in a tank M' in known fashion, and the moistened, gummed strip is fed by rolls 131x and 132x over a stationary 45 shear member 139x (see Fig. 7), into proximity to the path of the anvil plate V4, beneath the tool 128, 128x used for cutting off the patch sheet, and delivering it to the said anvil plate V4. 50

In pursuance of the invention, use is made of the forward movement of the anvil head-plate V4 to effect the disposition of the patch sheet PX in suitable alignment with the already clinched fastener 1, (see Fig. 10) below the squashing tool A3. To insure retention of the patch 55 sheet P3 on the anvil head plate V4 the latter is provided with ledges 223, each carried by a leaf-spring LS fixed at one end of a recess 224 in the lower face of the anvil head-plate V4, each ledge being biased by its spring, as shown in Figs. 6, 60 7 and 8, into an upper position which insures the embracement of the patch-sheet by the ledges, but permits retirement of the ledges under the action of the squashing tool A3. 65

After the squashing operation, the envelope passes from the squashing position over the stop fingers 54, which are retracted to permit this forward movement of delivering the envelopes in succession to a suitable hopper H, or other disposition of the envelopes, each of which now presents the appearance illustrated in Fig. 2 and shown in greater detail in Figs. 9 and 10. 70

From this disclosure it will be seen that without the intervention of any manual feeding operation, each envelope has been supplied with a 75

- clasp fastener, firmly secured thereto in accurate alignment with the concurrently formed hole 9 in the flap; and protective patches, P' and PX respectively, have been formed and applied in 5 permanently adhered position to the appropriate walls of the envelope, the patch PX completely covering the squashed inner end of the fastener.

I have described what I believe to be the best 10 embodiments of my invention. I do not wish, however, to be confined to the embodiments shown, but what I desire to cover by Letters Patent is set forth in the appended claims.

I claim:

1. In a machine for applying clasp fasteners 15 to envelopes of the class described; means for supporting a supply of envelopes; means for supporting a supply of fasteners; mechanism disposed at an applying station for riveting or clinching said fasteners to the bodies of said envelopes individually; mechanism for advancing 20 said envelopes seriatim from said supply thereof to the applying station; and mechanism for pressing a patch into adhesive engagement with said envelope-body, covering the clinched end of 25 said fastener.
2. In a machine for applying clasp fasteners to envelopes of the class described; means for supporting a supply of envelopes; means for supporting a supply of fasteners; mechanism disposed at an applying station for riveting or 30 clinching said fasteners to the bodies of said envelopes individually; mechanism for advancing said envelopes seriatim from said supply thereof to the applying station; and mechanism for pressing a patch into adhesive engagement with 35 said envelope-body, covering the clinched end of said fastener, said last-named mechanism being adapted to embed said clinched fastener part into the contiguous faces of the patch and 40 envelope wall.
3. A machine for applying clasp fasteners to envelopes as claimed in claim 1, in which means are provided to present each envelope in turn at a station where a fastener blank is fed thereto 45 and clinched, and to a station where said clinched fastener is squashed.
4. A machine for applying clasp fasteners to envelopes as claimed in claim 1, in which means are provided to present each envelope in turn 50 at a station where a fastener blank is fed thereto and clinched, and to a station where said clinched fastener is squashed, said envelope movements respectively being performed in the general direction of travel of the envelopes.
5. A machine for applying clasp fasteners to envelopes as claimed in claim 1, in which means are provided to present each envelope in turn at a station where a fastener blank is fed thereto 55 and clinched, and to a station where said clinched fastener is squashed, and in which a protective patch is applied to the exposed inner end of said squashed fastener.
6. In a machine for applying clasp fasteners to envelopes of the class described, means for supporting a supply of envelopes; means for supporting a supply of clasp fasteners of the type 60 having tongues; a mechanism for riveting said fasteners to the bodies of said envelopes seriatim; mechanism for transferring said envelopes from said supply thereof to the attaching station 65 and to deliver them therefrom to feed said envelopes with the fasteners attached; and means for actuating said transfer mechanism and said fastener-applying mechanism in timed relation; said machine being further characterized by having means to adhere to each flap a protective patch, and means acting concurrently to perforate the flap so reinforced, a hole to receive said fastener tongues; also by means 70 to apply a protective patch to the riveted fastener.

ized by having means to adhere to each flap a protective patch, and means acting concurrently to perforate the flap so reinforced, to provide a hole to receive said fastener tongues; also by means to apply a protective patch to the riveted fastener and to imbed the upset ends of the riveted fastener in contiguous surface of the patch and envelope material respectively.

7. In a machine for applying clasp fasteners to envelopes of the class described, means for supporting a supply of envelopes; means for supporting a supply of fasteners; a mechanism for attaching said fasteners to said envelopes seriatim; mechanism for transferring said envelopes from said supply thereof to the attaching station and to deliver them therefrom to feed said envelopes with the fasteners attached, means for actuating said transfer mechanism and said fastener-applying mechanism in timed relation; said fastener-applying mechanism including a 20 fastener-clinching station and a fastener squashing station, each comprising a main anvil, a plunger tool reciprocable relatively thereto, and a movable anvil reciprocable to and from a position intermediate said main anvil and said 25 plunger, at each of said stations.

8. A machine for applying clasp-fasteners to envelopes as claimed in claim 7, in which means are provided at the squashing station for applying a patch to the inner end of said squashed 30 eyelet, at the time of squashing.

9. A machine for applying clasp-fasteners to envelopes as claimed in claim 7, in which means are provided at the squashing station for applying a patch to the inner end of said squashed 35 eyelet, at the time of squashing, said means comprising a support for a supply of gummed patch strip, means to remoisten and feed the leading end of said strip into intersecting relation with the path of travel of the envelopes, means to cut 40 off a patch sheet, and means to transfer said patch sheet into the envelope preliminary to the squashing operation.

10. A machine for applying clasp-fasteners to envelopes as claimed in claim 7, in which means 45 are provided at the squashing station for applying a patch to the inner end of said squashed eyelet, at the time of squashing, said means comprising a support for a supply of gummed patch strip, means to remoisten and feed the leading 50 end of said strip into intersecting relation with the path of travel of the envelope, means to cut off a patch sheet, and means to transfer said patch sheet into the envelope preliminary to the squashing operation, said last-named means 55 being constituted by a part of the anvil used in the squashing mechanism.

11. In a machine for applying clasp fasteners to envelopes of the class described, means for supporting a supply of envelopes; means for supporting a supply of clasp fasteners of the type having tongues; a mechanism for rivetting said fasteners to the bodies of said envelopes seriatim; mechanism for transferring said envelopes from said supply thereof to the attaching station 65 and to deliver them therefrom to feed said envelopes with the fasteners attached; and means for actuating said transfer mechanism and said fastener-applying mechanism in timed relation; said machine being further characterized by having means to adhere to each flap a protective patch, and means acting concurrently to perforate the flap so reinforced, a hole to receive said fastener tongues; also by means 70 to apply a protective patch to the riveted fastener.

tener and to imbed the upset ends of the riveted fastener in contiguous surfaces of the patch and envelope material respectively, said mechanisms for feeding patch stock to be added to the envelopes being organized to operate respectively from positions disposed laterally with respect to the general path of travel of the envelopes.

12. A machine for applying clasp-fasteners to envelopes as claimed in claim 6, in which means are provided at the squashing station for applying a patch to the inner end of said squashed eyelet, at the time of squashing, said means com-

prising a support for a supply of gummed patch strip, means to remoisten and feed the leading end of said strip into intersecting relation with the path of travel of the envelope, means to cut off a patch sheet, and means to transfer said patch sheet into the envelope preliminary to the squashing operation, said last-named means being constituted by a part of the anvil head-plate of the squashing mechanism, the latter having a retaining projection and means to bias 10 said projection into retentive position, yieldingly.

ABRAHAM NOVICK.
